UNITED STATES PATENT OFFICE.

HERMAN C. BREHMER, OF PHILADELPHIA, PENNSYLVANIA, ASSIGNOR TO H. W. BUTTERWORTH & SONS' CO., A CORPORATION OF PENNSYLVANIA.

ATOMIZER.

1,423,989.

Specification of Letters Patent. Patented July 25, 1922.

Application filed July 31, 1919. Serial No. 314,583.

To all whom it may concern:

Be it known that I, HERMAN C. BREHMER, a citizen of the United States, and resident of Philadelphia, county of Philadelphia, and State of Pennsylvania, have invented an Improvement in Atomizers, of which the following is a specification.

The object of my invention is to provide a construction of atomizer, especially useful 10 in treatment of textile fabrics, which will insure a most thorough vaporization of the liquid with a given minimum blast pressure, whereby a uniform moist atmosphere may be obtained throughout the chamber 15 through which the fabric is passed.

More particularly my object is to provide the atomizers individually with nozzles respectively for blast pressure and liquid, arranged at an angle to each other and relatively 20 adjustable in a common frame to bring the orifices into different adjusted positions relatively to each other; and preferably, so that each nozzle may be adjusted axially in the frame to and from the axial 25 line of the other nozzle.

In practice, these nozzles are usually employed in batteries arranged within a common tank having means for maintaining a constant water level to insure a definite and 30 constant lift for the water to the atomizer nozzle, and the atomizers are sustained by horizontal blast or pressure pipes upon which they are mounted, the construction providing fixed blast nozzles upon which is 35 mounted a vertically adjustable frame in which is mounted the water nozzle having one end extending down below the water level in the tank and the other or nozzle end arranged horizontally in alinement with 40 a vertical plane through the axial line of the blast or pressure nozzle and preferably adjustable to or from the axial line of said nozzle.

My invention also consists of improvements hereinafter described whereby the above objects and results are attained, said improvements comprising certain organization and combination of parts which are fully described hereinafter and more particularly 50 defined in the claims.

Referring to the drawings: Fig. 1 is a plan view of a portion of a tank with my improved atomizers applied thereto; Fig. 2 is a vertical sectional view of the same; Fig. 55 3 is a sectional elevation of the nozzle struc-

ture embodying my invention; and Fig. 4 is a perspective view of the connecting frame between the blast and fluid nozzles.

9 is a tank having an overflow pipe 10 to insure a constant level of water therein and 60 11 is a water supply pipe for supplying water to the tank. 2 are horizontal pressure or blast pipes and extend through the sides of the tank and are sustained thereby at a level preferably just below the water 65 level, as shown in Fig. 3. These pipes 2 may be supplied with compressed air or other pressure medium (as steam if desired), by pipes 15 and 16, connecting with pressure pipe 13, and pressure from which may be 70 shut off or controlled by suitable valves 14, of which there may be a separate valve for each pipe 2. 12 represents a side wall of the textile machine in which the tank 9 is located. From the upper part of the pipes 75 2 there extend the vertical blast or pressure nozzle pipes 3 upon which are respectively mounted the remaining parts of the atomizers proper.

Referring to Fig. 3, it will be seen that the 80 blast nozzle 3 is conical at the top having a small orifice centrally arranged and is also screw threaded upon its outer surface at 26. Sleeved upon the upright blast nozzle 3 is a right-angled frame 4 having a hole 18 which 85 fits the nozzle and a transverse slot 22 in which an adjusting wheel 25 is received, said wheel having a screw threaded hole and screwed upon the nozzle 3. In this manner the frame 4 may be adjusted to or from the 90 nozzle end 6 of nozzle 3. By turning the wheel 25 to the left, the frame 4 is moved upward toward the nozzle end 6 and when turned to the right, the frame is moved downward. The other or upright arm of 95 the frame 4 is provided with a horizontal hole 17 and a transverse slot 21 of similar construction to the parts 18 and 22, but said sets of parts of the two arms of the frame are at right angles to each other. 5 is a 100 horizontal water nozzle having a conical end and nozzle aperture, corresponding to blast nozzle 3; and similarly, it is provided with a screw threaded outer surface 24. This horizontal water nozzle is inserted through 105 the horizontal hole 17 of the frame 4 and has its supply or suction end 7 extended down into the water 8 in the tank 9. The nozzle 5 is also provided with an adjusting wheel 23 fitting the slot 21 in the frame 4 110

and screwed upon the screw threads 24 of the nozzle, whereby a rotation to the left adjusts the nozzle and toward the axis of the blast nozzle 3 and a rotation to the right adjusts it in the reverse direction.

By the construction shown, the water nozzle 5 is supported from the blast nozzle 3; and by the frame 4 and adjusting wheels 25 and 23 the nozzle 5 may be adjusted both vertically and horizontally with respect to the nozzle 3 to provide the proper relation of the two orifices of the nozzles, whereby the best results may be obtained. If the air blast from nozzle 3 is relatively low in pressure, it is desirable to lower the nozzle 5 so that not only is the lift required to be less but the effectiveness of the blast from nozzle 3 to atomize the water is increased, this latter being assured by the horizontal adjustment also of nozzle 5.

To prevent any relative shifting of the nozzles after having been adjusted, I provide the frame 4 with a slot 19 extending throughout its body from hole 17 to hole 18 and also with a transverse clamping screw 20 by which the two parts, on either side of the slot, may be drawn together to cause the hole portions 17 and 18 to grip and hold the nozzles 3 and 5 respectively.

The essential feature of my invention resides in the capacity for relative adjustment of the two nozzles 3 and 5, whereby the desired mist or vapor may be secured with any given blast pressure, whether it be compressed air or steam. While the atomizers are ordinarily used to vaporize water, it is manifest that they may be employed to vaporize chemical solutions for various purposes.

In use with textile machinery the atomizers are arranged along the lengths of pipe 2 in any numbers found necessary, as will be understood by reference to Fig. 1.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention what I claim as new and desire to secure by Letters Patent, is:—

1. An atomizer consisting of a liquid holding tank, a vertical blast nozzle rigidly positioned in the tank, combined with an adjustable horizontal liquid supplying nozzle arranged at an angle to the blast nozzle and above the liquid level in the tank, said nozzles having conical ends so as to be capable of

having the two nozzle apertures brought very close together under adjustment, said liquid nozzle having a downward pipe extending a substantial distance into the tank, a connecting frame adjustably secured upon the vertical blast nozzle so as to be raised or lowered in respect thereto and having an upwardly extending part for supporting the horizontal portion of the liquid supplying nozzle, and means for adjusting the liquid supplying nozzle upon the frame.

2. An atomizer consisting of a liquid nozzle, a blast nozzle at right angles to the liquid nozzle, a slotted frame having guiding and clamping apertures therethrough through which the nozzles extend, and a single clamping device for the slotted frame whereby it may be made to simultaneously clamp both of the nozzles in relative adjusted positions.

3. An atomizer consisting of an upwardly directed blast nozzle, combined with a rigid frame vertically adjustable thereon to and from its orifice, and a liquid nozzle supported by and horizontally adjustable in the frame at right angles to the blast nozzle so as to be movable to and from said blast nozzle, while retaining the same right angled relative position to it, said liquid nozzle having a downwardly extending suction pipe.

4. The invention according to claim 3, wherein the frame is provided with means for adjustably clamping it to each of the nozzles.

5. An atomizer consisting of a vertical nozzle having a screw threaded exterior and a second nozzle at an angle to the first mentioned nozzle and also having a screw threaded exterior, combined with a frame having apertures through which the two nozzles are guided with freedom of longitudinal movement, two wheel shaped parts held in the frame and having screw threaded holes respectively engaging the screw threaded portions of the two nozzles whereby said nozzles may each have a relative adjustment, and means for supplying a liquid to one of the nozzles and a blast pressure to the other.

6. An atomizer consisting of a vertical nozzle having a screw threaded exterior and a second nozzle at an angle to the first mentioned nozzle and also having a screw threaded exterior, combined with a frame having apertures through which the two nozzles are guided, wheel shaped parts held in the frame and having screw threaded holes respectively engaging the screw threaded portions of the nozzles whereby said nozzles may have a relative adjustment, means for clamping the nozzles in the frame when adjusted, and means for supplying a liquid to one of the nozzles and a blast pressure to the other.

7. An atomizer comprising a vertical blast nozzle and a horizontal nozzle for supplying

liquid, combined with an angle frame having guide holes for the nozzle and said holes crossed by slots and said frame also slotted from hole to hole in the plane of their axes, 5 wheel shaped parts fitting the crossing slots and screwed upon the nozzles for adjusting them, and a transverse clamping screw for drawing the two portions of the frame, which are formed by the slot extending between the two holes, together to clamp the nozzles in the holes of the frame when adjusted.

8. In an atomizer, the combination of a tank having means for maintaining a constant liquid level, a horizontal blast pipe therein, a plurality of atomizers secured to said pipe and respectively comprising a vertical blast nozzle, a horizontal liquid nozzle having a downwardly extending tube to receive liquid from the tank, an angle frame 15 adjustable vertically upon the vertical blast

nozzle and carrying the horizontal liquid nozzle, and means for clamping the frame in adjusted relation to the nozzles.

9. In an atomizer, the combination of a tank having means for maintaining a constant liquid level, a horizontal blast pipe therein, a plurality of atomizers secured to said pipe and respectively comprising a vertical blast nozzle, a horizontal liquid nozzle 20 having a downwardly extending tube to receive liquid from the tank, an angle frame adjustable vertically upon the vertical blast nozzle and carrying the horizontal liquid nozzle, means for adjusting the liquid nozzle horizontally in the angle frame, and means for clamping the frame in adjusted relation to the nozzles.

In testimony of which invention, I hereunto set my hand.

HERMAN C. BREHMER.
